(57) **CLAIM**

The ornamental design for a stream straightener for faucet, as shown and described.

DESCRIPTION

FIG. 1 is a top plan view of a first embodiment of a stream straightener for faucet in accordance with my design; FIG. 2 is a top, front, right perspective view thereof; FIG. 3 is a bottom view thereof;

FIG. 4 is a bottom, rear, left perspective view thereof; and FIG. 5 is a right side elevational view thereof;

FIG. 6 is a top plan view of a second embodiment of a stream straightener for faucet in accordance with my design; FIG. 7 is a top, front, right perspective view thereof;

FIG. 8 is a bottom view thereof; FIG. 9 is a bottom, rear, left perspective view thereof; and FIG. 10 is a right side elevational view thereof;

FIG. 11 is a top plan view of a third embodiment of a stream straightener for faucet in accordance with my design; FIG. 12 is a top, front, right perspective view thereof; FIG. 13 is a bottom view thereof;

FIG. 14 is a bottom, rear, left perspective view thereof; and, FIG. 15 is a right side elevational view thereof.
